UNITED STATES PATENT OFFICE.

IRVING A. DELINE, OF DENVER, COLORADO.

AUTOMATICALLY-OPERATING PAPER-BOX SHAPING AND FINISHING MACHINE.

Application filed May 16, 1927. Serial No. 191,784.

My invention relates to an automatically operating paper box shaping and finishing machine.

The object of the invention is to provide a 5 rotatable support having a circular series of mechanisms thereon for forming and clamping the bands of paste board boxes in order to enable the ordinary tops or bottoms as the case may be, to be secured thereto, and 10 then, the extension tops or bottoms; said support having an intermittent rotary movement, thereby permitting an attendant to accomplish the first stage of the work on each of a series of boxes in successive order, while 15 the support is at rest, the second stage of the work commencing with the first box of the series when the support has made a complete rotation.

Further, to provide a circular table having 20 an intermittent rotary movement and provided with an endless series of mechanisms for forming the band portions of paste board boxes into any one of a variety of shapes, and clamping said band portions 25 while the bottoms or tops, as the case may be, and then the extensions are secured thereto by an attendant during one complete rotation of the table; the extension bottoms or tops being adhesively secured to the original 30 bottoms or tops and clamped thereon, the boxes being removed in successive order upon the next rotation of the table.

Further, to provide a rotary series of band forming and clamping devices, each of which 35 comprises a form of any desired outline and manually operated dies which conform to the shape of the form and which are adapted to clamp a band around said form and hold 40 said band while the usual bottom or top is secured thereto, and while an extension bottom or top is secured to the usual bottom or top, means being provided for clamping said extension bottom or top in place, and holding 45 the same until the last box of the series is completed, all of the parts being thus held in accurate relation until the adhesive material is set.

These and other objects which will hereinafter appear, are accomplished by the apparatus illustrated in the accompanying drawings in which:—

Figure 1, is a plan view of the improved box band forming and clamping apparatus

constructed in accordance with my invention, a part being omitted and a part being 65 broken away for clearer illustrations.

Figure 2, is a side view of the same.

Figure 3, is a plan view, enlarged, of the mechanism for imparting an intermittent rotary movement to the table which supports 60 the band forming and clamping devices.

Figure 4, is a sectional elevation of the driving member of the table rotating mechanism shown in Fig. 3, and the worm gearing 65 for retarding the same.

Figure 5, is a longitudinal sectional view—enlarged-through one of the band forming and clamping mechanisms, on the line 5—5 of Fig. 1, the frames being in open position, the extension bottom clamp being 70 omitted.

Figure 5^A, is also a sectional view showing the frames in closed position, the form and dies being omitted.

Figure 6, is a transverse sectional view 75 thereof on the line 6—6 of Fig. 1.

Figure 7, is a bottom plan view of one of the box forming and clamping mechanisms.

Figure 8, is a top view of the same, the band forming and clamping dies being 80 omitted but shown in dotted lines.

Figure 9, is a vertical sectional view of the operating and locking device for the extension bottom clamping block.

Figure 10, is an enlarged sectional view 85 through the plate shown in Fig. 9, to which the presser block is secured.

Figure 11, is a plan view of one of the box forming and clamping elements showing removable means used in connection therewith when making single layer boxes or boxes of half the usual depth, the box forming block being omitted but shown in dotted lines.

Figure 12, is an enlarged sectional view on 95 the line 12—12 of Figure 11.

Figure 13, is a perspective view of a band and strip surrounding the same as they appear before placed in the former.

Figure 14, is a sectional view showing the 100 band united to the usual top or bottom by the bent-over portion of the strip.

Figure 15, is a sectional view showing the extension top or bottom secured to the usual top or bottom.

Figure 16, is a bottom view of one of the 105

band forming and clamping mechanisms showing a modification in the manner of closing the dies upon the form.

Figure 17, is a similar view showing the manner of operating two pairs of dies, the pairs moving in paths at right angles to each other.

Figure 18, is a fragmental view similar to Figure 17, but showing cables for operating the die frames instead of rods.

Figure 19, is a plan view showing dies arranged for forming three box bands simultaneously, also showing a modification in the sliding connection of the die frames with the stationary plate.

Figure 20, is an enlarged fragmental sectional view on the line 20—20 of Figure 19.

Figure 21, is an enlarged fragmental sectional view of the line 21—21 of Figure 16.

Figure 22, is a side view of a further modification in the mechanism for opening and closing the dies.

Figure 23, is a front end view of Fig. 22, and

Figure 24, is a plan view thereof, on a smaller scale, the dies and form being omitted but shown in dotted lines, and the form-supporting plate being broken away to permit an unobstructed view of the mechanism beneath the same.

Referring to the accompanying drawings:

The numeral 1, indicates a supporting structure which is made up of connected rectangular side, end and top frames, a platform 2, being supported on the lower members of opposite side frames, as shown in Fig. 2. Upon the platform 2, is secured a metal base plate 3, having a bearing socket 4, near its inner end, vertical brackets or uprights 5 on its outer end and a vertical upright 6 intermediate of its ends. To the uprights 5 and 6 is bolted a gear housing, comprising a horizontal hollow cylindrical part 7, having a flat hollow extension 8, to which is bolted a hollow semi-circular cap 9, the extension 8 and the cap 9 having registering bolt flanges 10 which are connected by bolts 11 as shown in Fig. 3. Axial hubs 12 and 13 are formed in opposite sides of the flat part of the housing; one half of each hub being formed on the extension 8, and the other half on the cap 9.

The cylindrical part 7 of the housing is formed with a horizontal projection 14 having depending lugs 15 which are bolted to the uprights 5 and the cap 9 is formed with a depending lug 16 which is bolted to the upright 6 as clearly shown in Fig. 4, a short shaft 17 is mounted in the hubs 12 and 13 and on the lower portion of this shaft is keyed or otherwise secured a worm gear 18 which is enclosed by the extension 8 and its cap 9 and this gear meshes with a worm pinion 19 in the cylindrical housing 7, which pinion is secured upon a shaft 20 which is

journaled in caps 7^A which are bolted to the ends of the cylinder 7.

The shaft 20 extends beyond one end of the cylinder 7 and its end portion is mounted in a bearing 21 which is bolted to the adjacent side of the supporting structure 1. A stepped belt wheel 22 is secured upon the shaft 20 and this wheel is connected by a belt 23, with a stepped pulley 24 which is secured upon a shaft 25 which is mounted in bearings secured to the opposite side of structure 1 from the shaft 20. The shaft 25 has a belt wheel 26 secured upon one end thereof, which is connected by a belt 27 with a small pulley 28 on the shaft of an electric motor 29 which is bolted to the platform 2.

Thus, power from the motor 29 is communicated by the belt 27 to the wheel 26, the shaft 25 and stepped pulley 24 and thence by belt 23 to wheel 22 on the shaft 20 and thence by worm pinion 19 and worm gear 18 to the shaft 17.

Upon the upper portion of the shaft 17 is secured a disk or wheel 30 having a hub 31 which rests on the hub 12 of the gear housing 8—9. The disk 30 has formed thereon or secured thereto a short, radial arm or lug 31 which extends slightly beyond the circumferential edge of the disk, the under side of the lug being slightly above the upper side of the disk as clearly shown in Fig. 4. The lug 31 has a hole in which is threaded or otherwise secured, a bolt or pin 32 which, upon each rotation of the disk 30, enters one of a series of radial slots or recesses 33 in the edge portion of a disk 34 which is secured upon a vertical shaft 35, the lower end of which is mounted in the socket bearing 4 of the base plate 3. There are six radial slots 33 in the disk 34, and upon each rotation of the disk 30, the pin 32 enters one of the slots 33 and turns the disk 34, one sixth of a complete rotation before the pin 32 passes out of this slot; the next succeeding slot 33 being in position to receive the pin when it intersects the circular path described by the open end of said slot. The purpose of the intermittent rotation of the disk 34 will hereinafter appear. The circumferential paths of the disks 30 and 34 intersect or overlap each other, as will be seen by reference to Fig. 3, and as both disks are on the same plane, this arrangement is provided for by inwardly curving the edge portions of the disks 34 between each two slots 33 in arcs 36 having the same radius as the circumference of the disk 30, so that the edge of the disk 30 will ride successively in the arcs 36, as the disk 34 is rotated by the disk 30. The edge portion 37 of the disk 34, on each side of the slots 33, represent the greatest diameter of the disk 34 and these portions of the disks 34 intersect or overlap the circumferential path of the disk 30.

as each slot 33 approaches and passes a line drawn through the axial centers of the disks, and therefore, the edge of the disk 30 is inwardly curved at 38 on an arc whose center is on a line which passes through the axial centers of the disk 30 and pin 32; thus the edge portion of the disk 34, having the greatest diameter rides in the curve 38 on each partial rotation of the disk 34 by the disk 30.

Upon the top of the support 1 is secured a pair of parallel bars 39 upon which rests a circular metal plate 40 which is bolted to said bars and is provided with an axial hole through which the shaft 35 passes. The plate 40 is provided with a circular ball race which is supplied with balls 41 upon which rests a plate 42 also having a ball race. The plate 42 is integrally connected by a hub 43, and ribs 44 with a larger plate 45 which constitutes the base plate for a circular table, to be presently described and the shaft 35 extends through an axial opening in the hub 43 and a suitable distance above the base plate 45 for a purpose which will later appear. A set screw 46 in the hub 43 is screwed against the shaft 35 and thus rigidly secures the base plate 45 and its plate 42 to the said shaft 35.

To the top face of the base plate 45 are bolted a series of radial bars 47, preferably channel bars and six in number as shown in Fig. 1, and the outer ends of these channel bars are connected by a circular angle bar 48, as shown in Figures 1 and 5, the circular bar 48 being about seven feet in diameter.

The radial bars 47 are further connected by segmental angle bars 49 which are concentric with the circular bar 48 and a suitable distance from the same, and upon the horizontal members of the bars 48 and 49 are secured segmental table sections 50 in the form of wooden blocks which together make up a ring-like table which supports the box forming and clamping mechanisms which will now be described.

There are preferably six of these mechanisms and as they are identical in construction a description of one will suffice.

Upon the table sections 50, and above the outer end portions of each of the radial channel bars 47, is a horizontal metal plate 51 which is supported upon spacing tubes 52, which rest upon the table sections and the plates are held in place by bolts 53 which pass through the plate, the spacing tubes and the table sections, nuts being screwed upon the bolts and against the under sides of the table. The plates are thus supported a suitable distance above the table to permit the securing of mechanism to their under sides, as will hereinafter appear. Upon the two opposite side edges of each plate 51 are secured slideway bars 54 by bolts 55, the outer edges of the bars being V-shaped in

cross section. Upon the V-shaped edges of these bars are mounted opposite pairs of slides 56 and 57, comprising grooved bars formed with right angled plates 58 on their outer ends, which are braced by integral webs 59 connecting them with the slides, as shown in Fig. 8. The end plates 58 of the slides 56 are connected by a wooden bar 60 and this bar and its slides will hereinafter be designated as the frame A. The end plates of the slides 57 are connected by a similar wooden bar 61, and this bar and its slides will hereinafter be designated as the frame B, and these bars with their slides are moved toward and away from each other in the following manner:—Upon the undersides of the slideways 54 are integral, depending lugs 62 and 63, the lugs 62 having pins upon which are rotatably mounted gears 64, while a rod or shaft 65 extends through the lugs 63, and has rigidly mounted thereon gears 66, which mesh with the gears 64. These gears may be segmental as in practice, they make only about a quarter of a complete rotation.

The gears 66 are formed with radial extensions 67 to which are pivotally attached the inner ends of rods 68, the outer ends of which pass through bushings 69, which are loosely mounted in depending brackets 70, which preferably form an integral part of the slide plates 57. The bushings 69 are held in place by nuts 71 which are screwed upon the outer ends of the rods 68. The gears 64 are formed on their inner faces with arm-like enlargements 72 which extend beyond the peripheries of said gears, and to the outer ends of said enlargements are pivotally secured the inner ends of rods 73, the outer ends of which pass through bushings 74 which are loosely mounted in depending brackets 75 formed on the end plates 58 of the slides 56, the bushings 74 being held in place by nuts 76 which are screwed upon the ends of the rods 73. One end of the shaft 65 extends beyond the adjacent bearing lug 63 and is provided with an operating handle 77. By reference to Fig. 5, it will be seen that when the handle 77 is swung in the direction of the arrow, the gears 66 will draw upon the rods 68, and move the cross bar 61 and its slide bars 57, inward and that simultaneously the gears 64 will draw upon the rods 73, and also move the cross bar 60 and its slide bars 56 inward; the purpose of movements being hereinafter set forth.

To the under side of the cross bar 60 are secured a pair of spaced inwardly extending horizontal abutment brackets 78; and upon the under side of the cross bar 61 are also secured a pair of similar abutment brackets 79; the brackets on one bar being in direct line with those on the opposite bar. These brackets are in the form, substantially, of

flat narrow castings, the inner ends of which terminate in depending right angled aperture shoulders 80.

In the aperture shoulders of each pair of lined abutments 78—79 is loosely mounted a tube or rod 81, which is held against displacement by pins 82 which are passed through the end portions of the rods back of the shoulders 80, as clearly shown in Fig. 7. Upon each rod 81 is placed a coil spring 83 which is held under slight compression between the shoulders of the opposing abutments, and these springs cushion the inward movements of the cross bars 60 and 61 for a purpose which will later appear.

Near the outer edge of the plate 51 and on one side of the center thereof is secured a pair of depending brackets 84 in which is mounted a rod or shaft 85, the inner end portion of which is bent at right angles to form a lever arm 86, for a purpose which will later appear, and which is bent in a manner shown in Fig. 5. The outer end of rod or shaft 85 extends beyond the adjacent side of the plate 51 and is provided with an operating handle 87, the latter handle being on the opposite side of the plate from the handle 77 on the rod 65.

Upon the upper side of the plate 51 is secured by screws, a block 88, which may be of any desired shape, such as round, square, hexagonal, heart-shaped, etc., the block in the present instance, being heart-shaped. This block determined the shape 35 of the box and therefore is removably secured to the plate so that other blocks may be employed for any one of a variety of styles of boxes. Cooperating with the block 88 is a pair of formers or dies which taken 40 together are of the same shape or outline as the block 88, and one of these dies 89 is removably secured to the frame A and the other die 90 is removably secured to the frame B.

To the under side of the die 89, adjacent the side edges thereof, are bolted thin metal plates 91 (see Fig. 6) which extend beyond the sides of the die and rest upon and are bolted to the slides 56.

Similar plates 92 are bolted to the under side of the die 90 and rest upon and are bolted to the slides 57. Thus, when the frame A—B is open, the dies are moved away from the block 88 and when the frame 55 is closed the dies engage the block, or rather the box band which surrounds the said block, and presses the band against the block at all points, as will later be more fully described. The block 88 is formed with a relatively large circular aperture 93, which is concentric with a small circular aperture 94 in the plate 51, the latter aperture being surrounded by a boss 95, and the aperture 93 in the block accommodates a plunger 96 for 60 removing a completed box from the block

or form 88. The plunger 96 is in the form of a wooden disk, to the under side of which is secured a thin metal disk 97 having a central threaded aperture surrounded by a boss 98, which normally rests upon the boss 95 of the plate 51, the upper face of the plunger being normally flush with the upper faces of the dies 89 and 90. An eye bolt 99 is screwed into the metal disk 97 and extends down through the hole 94 in the plate 51, and the end portion of the lever arm 86 passes through the eye of this bolt, as shown in Figures 5 and 7; so that when the handle 87 of the rod or shaft is swung outward, the lever arm 86 raises the plunger 96 and thus removes a box from the form 88 by a direct vertical push, by which binding of the box band upon the form is prevented.

On the left side of each frame A—B and close to the same is a vertical standard 100 in the form of a section of tubing which is secured at its lower end in hub portion of a circular plate 101 which is secured to the table. A tube or sleeve 102 of less length than the standard 100, is placed over the said standard so as to rest on the hub of the plate 101, and a horizontal bar 103 is pivotally mounted on the standard in the following manner:—This bar is preferably in the form of a channel bar upon one end of which is bolted a hinge member 104 having a hole through which the standard passes, the hinge member resting upon the upper end of the sleeve 102. A cap or nut 105 is screwed upon the upper end of the standard to hold the bar thereon, but permit the free swinging movement of the bar on the standard.

The opposite end of the bar has a casting 106 bolted thereon, the outer end of which is yoke shaped and is adapted to engage the upper portion of a standard 107 in the form of a tube which is secured at its lower end in the hub portion of a plate 108 which is secured to the table; this standard being close to the frame A—B and diametrically opposite the standard 100. A cap 109 is screwed upon the upper end of the standard 107, and is adapted to engage or nearly engage the yoke shaped casting 106, when the bar 103 is in the position shown in Fig. 6, 115 and thus cooperate with the cap 105 on the standard 100 in holding the bar against upward movement. A bracket C is bolted to the bar 103 midway of its length and this bracket comprises a body portion 110 having an upright bifurcated member 111, in the upper end of which is mounted a rod 7^B which extends beyond each side of the casting. Upon the rod 7^B is pivotally mounted the cam portion 112 of a vertically disposed lever 113.

The cam portion comprises a hub 7^A through which the rod 7^B passes, a socket member 7^C to receive a handle and the cam 7^D which is in the form of twin parallel 130

members which depend from the hub 7^A and which are curved on their lower ends to provide cam surfaces. These cam surfaces are adapted to engage the upper horizontal edges of twin projections 114 on an abutment 115 having a square opening extending vertically through the same, through which passes a square presser bar 116 to which the abutment 115 is adjustably secured by a set screw 117. The presser bar is slidably mounted in a corresponding guideway 118 in the body 110 of the bracket C, which is open on the side of the body next the swinging bar 103, so that the said swinging bar 15 confines the presser bar in its guideway as will be understood by reference to Fig. 9. The lower end of the presser bar terminates in a reduced threaded stem 7^E which is screwed into a sleeve or bushing 7^F which fits in a socketed hub 7^G on a substantially circular plate 119, and is held therein by a thumb screw 7^H.

The plate 119 is provided with diametrically opposite slots *a*, and a presser block 120 is secured to the plate by bolts *b*, which pass through the slots *a*, in the said plate.

The presser block 120 is of the same size and design as the extension bottoms and tops employed, these tops or bottoms extending about one half an inch beyond the circumferential edge of the ordinary or regular bottoms and tops. Lugs or ears *c* are formed at diametrically opposite points on the plate 119 and coil springs *d*, are connected at one end to the ears *c*, and at their opposite ends to the rod 7^B in the upper end of the bracket C. The threaded connection of the presser bar 116 with the sleeve in the hub of the plate 119, and the adjustable connection of the said plate with the presser block 120, permits of a vertical adjustment, a turning adjustment, and a back and forth adjustment of the presser block 120 with respect to form 88, or rather, the extension resting thereon, so that the presser block will exactly register with the said extension, and will exert the required pressure upon the said extension when depressed by the cam 7^D. When the lever or handle 113 is pulled forward, the cams 7^D ride on the projections 114 of the abutment 115 and the presser block 120 is thereby forced down upon an extension bottom or top, as the case may be, to clamp the same to the usual bottom or top, and hold it under pressure during a complete rotation of the table, during which period, the glue or other adhesive becomes set and the bottom or top is prevented from warping.

The die blocks 89 and 90 have secured thereon adjustable guides *e*, which center the extension top or bottom with respect to the block or form 88, when the said extension is placed thereon, as will later appear. When the presser block is depressed, the springs *d*,

are drawn upon or expanded and when the lever 113 is reversed, the springs *d*, contract, and raise the presser block, as will be understood by reference to Fig. 6. The bottom face of the presser block is preferably provided with a rubber pad *f*.

The operation of forming and clamping a box band, and securing thereto the regular bottom, and then the extension bottom in connection, is as follows, the word "extension" being used as applicable to either the top or bottom of the box, as the operation is the same in either case.

The bands F are cut in lengths to exactly conform to the outline of the block 88, whatever the shape of the block may be, and the ends of the band are connected by a narrow strip of tape G, so that the band is in the form of a ring. A strip H is then glued to the band, through the instrumentality of a suitable stripping machine, which is not illustrated as it forms no part of the present invention, and this strip is preferably about one inch wider than the band and extends a half inch beyond each edge of the band. One edge portion of this strip is bent over the edge of the band and adhered to the inner face of the band, but the other edge of the strip is left unfolded as shown in Figure 13, and the band is then ready to be placed on the forming block 88.

The mechanism for rotating the table is set in motion and this mechanism can be governed to move the table intermittently after such intervals that the periods when the table is at rest will be of sufficient duration to enable the attendant to perform the necessary work in the production of a box. The attendant first swings the bar 103 back to the position shown in any one of the mechanisms on the right side of Fig. 1, so that the presser block 120 will be out of the way, and the handle 77 is pulled forward to permit the frames A and B to slide apart under the expansive action of the springs 83. The regular bottom I is then placed on the block 88 and the band is placed around this said block with the unfolded edge of the strip H uppermost, and is pressed down until it rests upon the plate 51, the band being about one sixteenth of an inch wider than the thickness of the block 88 so as to surround the bottom I, as shown in Figures 14 and 15. The attendant then swings the handle 77 inward whereby the intermeshing gears 64 and 66 are caused to draw upon the rods 73 and 68, which in turn draw upon the frames A and B, and the dies or formers 89 and 90 are thereby moved inward against the band and clamp the same against the block 88 with a resilient pressure.

The unfolded portion of the strip H is then folded down upon the bottom I, thereby securing the bottom to the band. Glue is then applied to the bottom I around the

edge portion thereof or to the extension J as may be found most practicable and the extension J is placed upon the bottom I, the guides e, centering it so that it will be concentric with the band F, but will extend a half inch beyond the same at all points. The bar 103 is then swung to the position shown in Fig. 6, when the presser block 120 will be directly above the extension J and a slight distance from it, the lever 113 is drawn upon and the presser block is forced down upon the extension J in the manner before described, and the said extension is thus clamped against the box bottom and so held until the table makes a complete rotation during which time the glue has become set, and this part of the box is completed.

The operation is repeated until six half boxes have been completed, when the table will have made a complete rotation, and the first half box of the series is ready to be removed. The attendant then pushes the lever 113 which releases the cams 7^b and the presser block 120 is raised from the extension J by the springs d. The bar 103 is swung around so that the presser block will entirely uncover the extension J and the lever 77 is swung outward which permits the frames A and B together with the dies 89 and 90 to slide apart under the action of the springs 83. The lever 87 is then drawn upon to raise the plunger 96 in the manner previously described, and the plunger is thus forced against the bottom I and pushes the half box off the block 88.

When the frames A—B are open or apart as shown on the right side of Fig. 1, the gears 64 and 66 are in the positions shown in Fig. 5, and the pivoted connection between the rods 68 and the gears 66 is below the level of the shaft or rod 65, so that the line of push on the rods 68 is below the center of the shaft 65, thereby locking the frames in open position, the frames being pushed apart by the springs 83 and limited in their open movements by the pins 82, in the rods or tubes 81, which extend through the said springs, the pins 82 engaging the brackets 78, as will be understood by reference to Fig. 7. To the pivot pin 121 which connects one of the rods 73 of each frame A with the gear 64, is secured one end of a cable 122 which passes down through an opening in the table and over and around a sheave wheel 123, which is mounted in a bracket 124 which is secured to the under side of the table, as shown in Fig. 5.

The other end of this cable, connects with one end of a coil spring 125, the opposite end of which is secured to one end of a rod 126, the opposite end of which is secured to one of the radial channel bars 47, (see Fig. 1). When the lever 77 is operated in spreading the frames A and B apart the cable 122, draws upon the spring 125, thus

preventing a quick or sudden opening movement of the frames. When the lever 77 is operated to close the frames, the rods 73 are instantly acted upon and the frame A is first moved inward towards the block 88, but the rods 68 are not actuated until the gear 66 rotates sufficiently to shift the pull on the said rods 68 from below to above the center of the shaft 65, after which they will draw upon and move the frames B inward. When the frames are closed against the block 88, or rather against the band surrounding the block, the line of pull on the rods 73 is shifted from above, to below the center of the gears 64 as shown in Fig. 5^a, thereby locking the frames in closed position.

The spring 125 contracts as the frames close, and this spring, drawing under the pivot 121 which connects the inner end of the rod 73 to the gear 64, prevents the frames A and B from springing apart.

In Figures 11 and 12 is illustrated the means used in connection with the dies and form block in making half depth boxes or boxes for accommodating a single layer of goods. In carrying out this feature, I employ a pair of spacing blocks 127 and 128 which are half the thickness of the dies 88 and 89, the block 127 fitting in the box form recess, in the die 89 and the block 128 fitting in the corresponding recess in the die 90, these blocks resting upon the plate 51. The blocks 127 and 128 are held apart by coil springs 129 which surround rods 130, supported in alined holes in the opposing ends of the said blocks, the ends of the springs entering recesses in the ends of the blocks as shown. The form block 88^a, used in this connection, is slightly less than half the thickness of the dies, but flush with the top surface of the dies, and this form block is supported on a block 131 which is slightly more than one half the thickness of the dies thus defining a slight clearance space 132 between the form block, and the spacing blocks 127 and 128. The supporting block 131 is smaller than the form block 88^a, and the spacing blocks 127 and 128 are recessed to fit around the said supporting block, as clearly shown in Fig. 11. The former block and its supporting block are secured to the plate 51 by the same bolts 132. In this connection I may dispense with the wooden plunger block and use only a thin metal plunger plate or disk 133. When the attachment for making single layer boxes is used, the box band will rest upon the spacing blocks 127 and 128, as will be understood by reference to Figures 11 and 12, the box forming operation being the same as described in connection with full depth boxes.

The shaft 35 to which the table is secured, extends a suitable distance above the table, and a much smaller table 134 is secured thereon by means of a circular plate 135

which is secured to this table and is provided with a hub which registers with a hole in the table, the shaft 35 passing through the hub and the hole in the table, and the hub being secured to the shaft 35 by a set screw 136.

Bottoms, tops and extensions are placed upon the table 134 so as to be within easy reach of the attendant. A circular sheet metal plate 137 rests upon the radial channel bars 47 of the main table and closes the space between the inner ring 49 of the table and the shaft 35, thus hiding the said channel bars as well as the supporting mechanism and thereby adding to the artistic appearance of the table.

In Fig. 16, is shown a modification in the manner of closing the dies upon the form. In this arrangement, the gears 64 and 66 and the rods 68 and 73 are dispensed with, and the following mechanism is used: The under side of the plate 51 is formed with a boss or hub 3^A surrounding the hole through which the plunger operating eye bolt 99 passes, and upon the hub is rotatably mounted a disk 3^B, which is spaced from the plate 51 by a hub formed on the said disk as shown in Fig. 21. Adjacent the edge of the disk, or in opposite ears 3^C formed on the edge of the disk, are holes in which are pivotally secured the inner ends of rods 3^D and 3^E, one to the upper side of the disk and the other to the lower side thereof, as shown.

The outer ends of these rods are connected to eye bolts 3^F which pass through depending abutment plates 3^G secured to the cross bars 60 and 61 respectively. A coil spring 3^H is placed upon each eyebolt between the abutment plate and a washer which is held against the adjacent end of the spring by a nut 3^J. When the frames are open or apart, the disk 3^B is in the position shown in Fig. 16.

When the disk is turned in the direction of the arrow, the rods 3^D and 3^E are drawn upon, and the frames are drawn in and closed upon the form. When the dies engage the form, further pull on the rods is against the springs 3^H and when the line of pull on the rods passes the center of the disk, the dies will be locked against the form.

The disk 3^B is operated by a lever 3^K which is pivotally secured to the under side of the plate 51. The inner end of this lever is provided with a slot 3^L and is connected to the disk by a bolt or pin 3^M, which passes through the disk and through the slot 3^L. Other parts of the mechanism are the same as shown in the preceding figures.

In Fig. 17 is shown an adaptation of the rods and rotatable disk for operating four dies simultaneously. In this arrangement, rods 3^N are connected at their outer ends to eyebolts 3^F which pass through abutment plates 3^G on the pairs of die frames 3^P and 3^R which move in paths at right angles to

each other. The inner ends of the rods 3^N are pivotally connected in alternate order, to the upper and under sides of the rim portion of a disk 3^S which is secured to a hub on the plate 51 in the same manner as described in connection with the disk 3^B, the pivots connecting the rods with the disk being equidistant, and the disk being in the position shown, when the die frames are open.

The disk 3^S is operated by a lever 3^T the same as in the case of the lever 3^K. The die frames are each provided with parallel slides 3^U which move in guideways 3^V on the plate 51, thereby limiting the frames to direct in and out movements, and the inward movements of these frames are cushioned by springs 3^W which are interposed between the cross bars 3^X of the frames and abutments 3^Y on the plate 51, the springs 3^W surrounding rods 3^Z which are secured at one end to the cross bars and pass loosely through the abutments 3^Y thus holding the springs in place.

In Fig. 18 is shown an arrangement in which cables 4^A take the place of the rods 3^N and are connected to the disk and to the eyebolts in the same manner as the rods. These cables pass over sheave wheels 4^B which cause the cable to exert a direct pull on the die frames as will be understood by reference to the drawing. The cable bears upon the sheave wheel up to the point when its pivoted connection with the disk 3^S is in direct line with the center of the disk and with its eyebolt, and when the line of pull on the cable passes the center of the disk, the cable moves away from the sheave wheel, and the frames are locked.

In making very small boxes, the die blocks 4^E and 4^F are arranged to accommodate two or more of such boxes, for each box forming and clamping mechanism as shown in Fig. 19, and in this connection the plungers are dispensed with, and the finished boxes are removed by hand. In this connection it is also preferable to use a manually operated table so that the attendant or attendants may have sufficient time to complete each set of boxes before turning the table in position for the next set.

In Fig. 19, is also shown a modification in the sliding connection between the die blocks and the plate 51. In this arrangement upon two opposite sides of the plate are bolted three brackets 4^C, and in each set of brackets is secured a rod or track 4^D. Each die block is provided on opposite sides with pairs of slides 4^G in the form of brackets which are secured to the side edges of the die blocks and which are provided with lateral projections having apertures through which the rods or tracks 4^D pass. These brackets or slides support the die blocks at a slight distance above the table so as to permit their free back and forth movement, as will be understood by reference to Fig. 20.

This sliding arrangement can be used in connection with any means for operating the die frames.

In Figures 22, 23 and 24, I have shown a further modification in the mechanism for opening and closing the dies upon the form block. In this arrangement, the spacing tubes or sleeves 52 are dispensed with, and the metal plate 51 is supported upon opposite pairs of standards 138 and 138^A which are secured to the table sections 50. These standards, near their upper ends are formed with holes, and in the holes of each pair of standards is secured a rod or track 139. Upon each rod is mounted a pair of slides 140 and 141, in the form of flat bars having depending lugs or members 142 on their inner ends and longer depending members 143 on their outer ends, and the members 142 and 143 are provided with holes through which the rod or track 139 pass. To the slides 140 are secured the die 89, by screws 144, which extend down through slots in the side edges of the die and are screwed into the horizontal members of the slide, as shown. The die 90 is secured to the slides 141 in a similar manner by screws 145. By this arrangement, the dies are slidably mounted upon the track rods 139, to be moved back and forth with respect to the form block 88, and over the metal plate 51.

The outward movement of the die 89 is limited by engagement of the depending members 142 of the slide 140 with the adjacent standards 138, and the outward movement of the die 90 is limited by engagement of the depending members 142 of the slides 141 with the standards 138^A. A shaft 146, is rotatably mounted in bearing holes in the lower ends of the members 143 of the slides 140, and a similar shaft 147, is mounted in bearing holes in the lower ends of the members 143 of the slides 141. Upon the shaft 146 is rigidly mounted a pair of hubs 148, each having a depending arm 149 on one end and a sprocket wheel 150 on its other end.

To the lower ends of the arms 149 are pivotally attached socketed links 151 in which are secured the forward ends of a pair of rods 152, the opposite ends of which are slidably mounted in socketed members 153 which are mounted on the shaft 147, as clearly shown in Figs. 22 and 24.

Coil springs 154 surround the rods 152, and are held under tension between the ends of the links 151, and the socketed members 153. The sprocket wheels 150 perform only a partial rotation and therefore it is only necessary to provide them with teeth throughout a half or three-fourths of a complete circle. Sprocket chains 155 are secured at one end to the wheels 150, and pass over and around and under the said wheels, and extend forward slightly above the table top, and their opposite ends are secured to ears

156 which depend from the hub portions 157 of the socketed members 153.

The shaft 146 is provided with an operating handle 77, and the members 143 are connected by a channel bar 158 to hold them in rigid relation. As the arrangement shown in Figures 22 and 24, refers only to the die opening and closing mechanism, other features of the machine have been omitted in these views, but it will be understood that these features can be used in connection with the mechanism shown in Figures 22, 23 and 24, without any change in either their construction or arrangement.

The operation of the last described mechanism is as follows: Assuming that the dies 89 and 90 are closed upon the form 88, then the operating handle 77 is moved in the direction of the arrow, thereby turning the shaft 146, the arms 149 and the sprocket wheels 150. But as the lower ends of the arms 149 are pivotally connected to the links 151 which are under outward pressure from the springs 154, the said links form fulcrums for the arms 149, whereby the slides 140 with the dies 89 are moved outward on the track rods 139 until the depending lugs 142 engage the standards 138, and further outward movement of the die 89 is prevented.

The standards 138 now act as fulcrums and as the arms 149 are swung toward horizontal position, the links 151 push against the springs 154, which in turn push against the socketed members 153, and the slides 141, with the die 90, are slid outward upon the tracks 139, and away from the form block 88, until the depending members 142 on the said slides 141 engage the standards 138^A and prevent further movement of the slides.

Further movement of the arms 149 is now against the tension of the springs 154, and the rods 152 therefore, slide inward in the socketed members 153, until the line of push on the rods passes above the centers of the shafts 146 and 147, when the springs act to lock the arms 149, and thus hold the dies in open position. During these movements of the slides, the chains 155 unwind from the sprockets to permit such movement, as will be understood.

When the handle 77 is turned to close the dies, the chains 155 wind upon the sprocket wheels 150, and the slides 140 are thereby drawn inward until they contact with the form block, after which the chains draw the slides 141 inward until the die 90 also contacts with the form block, at which time the handle 77 passes a vertical line, the arms 149 are in vertical position and the springs 154 are under tension between the ends of the links 151 and the ends of the socket members 153, and thus lock the die in resilient contact with the form 88, as will be understood by reference to Fig. 22.

Instead of the sprockets and chains, I may employ belts and pulleys, the belts being secured at one end to the pulleys and at their opposite ends to the socket member

5 153.

Having described my invention, what I claim as new and desire to secure by Letters Patent, is:—

1. In mechanism of the character described, the combination with a circular table and means for imparting an intermittent rotary movement thereto; of an endless series of box band forming and clamping mechanism thereon, each comprising a horizontal plate having parallel guideways thereon, dies slidably mounted on said guideways, a form secured upon said plate between said dies, manually operated co-operating rotary elements and means connect-
10 ed therewith and with the dies for closing the dies upon the form and locking them in closed relation to clamp a box band about said form to facilitate the attachment thereto of a top and an extension on said top, and means for clamping the extension to the top.

2. In mechanism of the character described, the combination with a circular table and means for imparting an intermittent rotary movement thereto, of an endless series of box band forming and clamping mechanisms thereon, each comprising a horizontal plate having parallel guideways thereon, frames slidably mounted on said guideways, dies connected to said frames, a form secured to said plate between said dies, manually operated intermeshing gears on said plate and rods connected with said gears and said frames for closing said frames upon said form and locking them in closed relation thereby to clamp a box band about said form to facilitate the attachment thereto of a top and an extension on said top, and means for clamping the extension to the top.

3. In mechanism of the character described, the combination with a circular table and means for imparting an intermittent rotary movement thereto; of an endless series of box band forming and clamping mechanisms thereon, each comprising a horizontal plate having parallel guideways therein, frames slidably mounted on said guideways and dies connected to said frames, a form secured to said plate between said dies; manually operated intermeshing gears mounted on said plate and rods connecting said gears and said frames, said rods being drawn upon by the turning of the gears to close said dies upon said form and lock them in closed relation thereby to clamp a box band about said form to facilitate the attachment thereto of a top and an extension on said top, means interposed between said

frames tending to force them apart and means for clamping the extension to the top.

4. In mechanism of the character described, the combination with a circular table and means for imparting an intermittent rotary movement thereto, of an endless series of box band forming and clamping mechanism thereon each comprising a horizontal plate having parallel guideways, frames slidably mounted on said guideways, dies connected to said frames, a form secured to said plate between said dies, manually operated intermeshing gears on said plate, rods connecting said gears and said frames, the rods being drawn upon by the turning of the gears to close said dies upon said form, and lock them in closed relation thereby to clamp a box band about the form to facilitate the attachment thereto, of a top and an extension on said top, springs interposed between said frames tending to force them apart, a bar mounted to swing on a horizontal plane above said form, a spring controlled, cam operated presser on said bar to clamp the extension upon the top and hold the same under pressure.

5. In mechanism of the character described, a band forming and clamping device comprising a support having parallel guideways, dies slidably mounted on said guideways, springs interposed between said dies for normally forcing them apart, a form block supported between said dies, manually operated intermeshing gears on said support, and rods pivotally connected at one end to said gears and at their opposite ends to said dies, the rods being drawn upon by the turning of the gears to close said dies upon said form and lock them in closed relation thereby to clamp a box band about the form to facilitate the attachment thereto of a top, and an extension upon the top, a standard, a bar hinged thereto at one end to swing on a horizontal plane above the form, a spring controlled, cam operated presser on said bar to clamp the said extension upon the top and hold the same under pressure, a stop for said bar to define the position of the presser with relation to the extension, and means for removing the box from the form when the dies are opened and the presser is swung out of operative position.

6. In mechanism of the character described, the combination with a horizontal plate having parallel guideways thereon, opposing frames slidably mounted on said guideways and a form block on said plate between said frames, of a manually operated shaft mounted on said plate having gears rigidly secured thereon, rods pivotally secured at one end to said gears and at their opposite ends to one of said frames, gears in mesh with the first gears and rods pivot-

ally secured at one end to the latter gears and at their opposite ends to the other frame whereby when the shaft is turned in one direction the frames are drawn toward each other, dies removably secured to said frames and adapted to close upon said form block, springs interposed between said frames to normally force them apart, and resilient means for resisting the opening movement 10 of the frames.

7. In mechanism of the character described, the combination with a horizontal plate having parallel guideways, opposing frames slidably mounted thereon, dies removably secured to said frames and a form block secured to said plate between said dies; of a shaft mounted on said plate having an operating lever, gears rigid on said shaft, gears in mesh with the first gears, rods connecting the first gears and one of said frames, rods connecting the second gears and the other frame, whereby when the shaft is turned in one direction, the frames are drawn toward each other, abutments on said frames, rods loosely mounted in said abutments, coil springs surrounding said rods and bearing at their ends against said abutments, said springs tending to force said frames apart, stops on said rods to limit the outward movement of said frames, and a spring for resisting the opening movement of the frames.

8. In mechanism of the character described, the combination with a horizontal support having parallel guideways, opposing frames slidably mounted thereon, dies removably secured to said frames and a form block secured on said support between said dies; of a shaft mounted on said support having an operating handle, gears rigid on said shaft, and rods connecting said gears and one of the frames, gears in mesh with the first gears and rods connecting the latter gears and the other frame, whereby when the shaft is turned in one direction, the frames are drawn inward, a pulley mounted below said support, a flexible connection secured at one end to one of said gears and extending around said pulley, a coil spring connected at one end to the opposite end of said flexible connection, and to a fixed object at its other end, whereby when the shaft is turned to close the dies upon the form block the said spring resists the closing movement of the frames, abutments on said frames, springs interposed between said abutments to normally force said frames apart, means

for limiting the outward movement of the frames, a vertically movable plunger in said form block and means for operating the same.

9. In mechanism of the character described, the combination with a support, a form block thereon, dies slidably mounted on said support in cooperative relation to said form block and means for operating said dies; of a plunger vertically movable in said form block and having a depending element, a shaft mounted on said support having an operating handle on one end and a right angled lever arm on its opposite end which directly engages said depending element, whereby when the shaft is rocked in one direction, the plunger is lifted.

10. In mechanism of the character described, the combination with a support, a form mounted thereon and dies slidably mounted on said support in cooperative relation to said form for clamping a box band about said form to facilitate the attachment of a top to said band and an extension to said top, said form being of less thickness than said dies; of spacing blocks in the form engaging recess in said dies and beneath said form and means for holding said spacing blocks in said dies to move therewith, thereby to support a box band of less width than the thickness of the dies.

11. In mechanism of the character described, the combination with a support, co-operating dies slidably mounted on the support, a form between said dies and a supporting block for said form of less thickness than the thickness of the dies and of less area than said form, said form being flush with the top of said dies; of spacing blocks in the form engaging recesses of said dies and beneath said form, said spacing blocks being recessed to fit around said form supporting block, and springs interposed between said spacing blocks.

12. In mechanism of the character described, the combination with parallel track members, of cooperating dies slidably mounted on said track members, a support and a form thereon between said dies, a rotatable element on said support, means connecting said dies and said rotatable element, whereby when said element is turned said dies are drawn toward said form, and resilient means for normally forcing said dies apart.

In testimony whereof, I affix my signature.

IRVING A. DELINE.
